UNITED STATES PATENT OFFICE.

FREDERICK V. MALTBY, OF BRADFORD, PENNSYLVANIA.

TRAFFIC SIGNAL.

Application filed December 31, 1924. Serial No. 759,133.

This invention relates to an improved traffic signal for motor vehicles and seeks, among other objects, to provide a device of this character whereby a driver may conveniently indicate an intention to slow down or stop, to start or go straight ahead, to turn to the right, or to turn to the left.

The invention seeks, as a further object, to provide a device wherein the possibility of confusion as regards the particular signal displayed at any time, will be reduced to a minimum.

A still further object of the invention is to provide a device which, in addition to its function as a signal, will also serve to illuminate the license plate of the vehicle to which the device is attached, and wherein provision will be made for projecting the light rays in different directions according to the position of the device relative to the license plate.

And the invention seeks, as a still further object, to provide a device which will be efficient as well as ornamental and which may be readily installed.

Other and incidental objects will appear hereinafter.

In the accompanying drawings:

Figure 1 is an elevation showing my improved device mounted at the rear of a vehicle.

Figure 2 is a detail perspective view of the device.

Figure 3 is a front elevation of the device, the cover being removed.

Figure 4 is a vertical sectional view taken medially through the device.

Figure 5 is a transverse sectional view on the line 5—5 of Figure 4, looking in the direction indicated by the arrows.

Figure 6 is a fragmentary sectional view showing a slight modification of the invention.

In carrying the invention into effect, I employ a preferably rectangular casing 10 having a back wall 11, and extending through the back wall of the casing is a centrally disposed barrel 12 terminating flush with the forward edges of the casing. At its rear end, the barrel projects a short distance at the

rear of the casing and is closed by a dished reflector 13, at the larger end of which is an annular flange 14 extending radially from the barrel. Mounted axially of the reflector 13 is an appropriate lamp socket 15 removably accommodating a lamp 16, and formed in the projecting rear end of the barrel at

each side thereof, are, as particularly shown in Figure 5, windows 17 and 18 while at the lower side of the barrel is a like window 19. If desired, suitable transparencies may be provided for these windows. Fitting about the projecting rear end of the barrel is a spring clip 20 retained by the flange 14 of the barrel. As shown in Figure 5, the clip 20 is in the nature of a split band and when fitted about the rear end of the barrel is expanded considerably so as to firmly grip the barrel.

As shown in Figure 3, the barrel 12 provides a signal chamber 21 centrally of the casing 10, and extending from the barrel to the side walls of the casing are pairs of alined partitions 22 defining like signal chambers 23, 24, 25 and 26 respectively. The rear wall 11 of the casing is dished to provide reflectors 27 at the rear of said chambers and mounted axially of said reflectors are suitable lamp sockets 28 removably accommodating lamps 29, 30, 31 and 32, respectively.

Removably fitting over the casing is a cover 33 and clamped between the cover and the forward edges of the walls of the casing is a transparency 34 resting flat against the forward edges of the barrel 12 as well as the partitions 22. As shown in Figure 2, fastenings 35 are employed for securing the cover in position and, as brought out in this figure of the drawings, the cover is formed with a spider embodying a central circular band 36 from which extend pairs of oppositely disposed radial strips 37. The band 36 coincides with the forward end of the barrel 12 while the strips 37 coincide with the forward edges of the partitions 22 so that the transparency is thus divided into a number of areas 38, 39, 40, 41, and 42 corresponding in shape to the shape of the several chambers 21, 23, 24, 25 and 26, respectively. These areas are given different approved colors which are suitably imposed on the transparency. In the present instance, I have shown the area 38 red, the area 39 red, the area 40 yellow, the area 41 blue, and the area 42 green.

Fixed to the lower corner of the casing is a bracket 43 which is offset rearwardly and provided with a cross plate 44. This plate is apertured so that the plate may, as suggested in Figure 1, be readily attached to the cross bar of the tire carrier of a vehicle for supporting the device upon said bar above

the vehicle license plate, and it is now to be observed that the clip 20 is arranged to overlie the windows 17 and 18 at the rear end of the barrel 12 so that when the lamp 16 is 5 energized, light will be liberated through the window 19 for illuminating the license plate. The clip 20, therefore, serves to close the windows not in use and will also exclude dust and dirt as well as tend to reflect the 10 light rays through the window which is uncovered. Should the license plate be at the right of the device, the clip 20 is turned upon the barrel 12 to cover the windows 18 and 19 so that the window 17 will be left uncovered 15 to permit the illumination of the license plate, while should the license plate be at the left of the device, the clip 20 is turned upon the barrel to cover the windows 17 and 19 so that the window 18 will be left open 20 to permit illumination of the license plate. I accordingly provide a particularly convenient and effective arrangement in this respect.

A vehicle may, of course, be equipped with only a single one of the devices at the rear 25 of the vehicle, as shown in Figure 1, or, if preferred, one of the devices may be provided at the front of the vehicle as well as at the rear thereof. In any event, the several wires leading to the lamp sockets of the 30 device will be bunched into a cable, as suggested in Figure 4, and led to the instrument board of the vehicle, to the steering wheel, or other convenient location, where an appropriate switch will be provided for controlling the energization of the several 35 lamps. When intending to slow down or stop, the lamps 16 and 29 are preferably simultaneously energized so that, as will be seen in view of the foregoing description, the 40 red areas 38 and 39 of the transparency 34 will be illuminated for displaying a red signal light at each of said areas. If desired, the switch mechanism controlling the lamps 16 and 29 may be connected with the foot 45 brake of the vehicle so that the energization of said lamps will be accomplished automatically. When intending to start or go straight ahead, the lamps 16 and 30 are simultaneously energized so that a red light 50 will be displayed at the area 38 of the transparency while a yellow light will be displayed at the area 40. When intending to turn to the right, the lamps 16 and 41 are simultaneously energized so that a red light 55 will be displayed at the area 38 while a blue light will be displayed at the area 41 of the

transparency. Similarly, when intending to turn to the left, the lamps 16 and 32 are simultaneously energized so that a red light will be displayed at the area 38 while a green light will be displayed at the area 42 of the transparency. Thus, positive unmistakable signals will be given as to the intentions of the driver and in displaying a red light in connection with the other colored 60 lights, the attention of traffic will be directed to the signals. If desired, circuit connections may be provided whereby the lamp 16 may be used alone as a tail light or parking lamp. 70

In Figure 6 of the drawings, I have illustrated a slight modification of the invention wherein the front transparency 45 of the device is, at the front of the several signal chambers, provided with convex lens portions as indicated at 46. Otherwise, this modified structure is identical with the preferred construction and further description is accordingly believed unnecessary. 75

Having thus described the invention, what I claim is:

1. A traffic signal including a casing, a barrel extending into the casing and providing a central chamber, partitions in the casing defining a plurality of chambers grouped about said central chamber, a transparency closing all of said chambers, means for illuminating said chambers, the barrel projecting at the rear of the casing and being provided with a plurality of spaced windows, and means carried by the projecting portion of the barrel for uncovering any one of certain windows and coincidentally covering all of the remaining windows. 90

2. A traffic signal including a casing, a barrel extending into the casing and providing a central chamber, partitions in the casing defining a plurality of chambers grouped about said central chamber, a transparency closing all of said chambers, means for illuminating said chambers, the barrel projecting at the rear of the casing and being provided with a plurality of spaced windows, and a split spring clip gripped about the barrel and rotatably adjustable thereon for uncovering any one of certain windows between the ends of the clip and coincidentally covering all of the remaining windows. 100 105

In testimony whereof I affix my signature.

FREDERICK V. MALTBY. [L.S.]
